UNITED STATES PATENT OFFICE.

CHARLES K. MILLER, OF WAXAHACHIE, TEXAS, ASSIGNOR TO THE MOLINE PLOW COMPANY, OF MOLINE, ILLINOIS, A CORPORATION OF ILLINOIS.

MOLDBOARD FOR PLOWS.

1,159,063.

Specification of Letters Patent.

Patented Nov. 2, 1915.

Application filed May 10, 1912. Serial No. 696,441.

To all whom it may concern:

Be it known that I, CHARLES K. MILLER, a citizen of the United States, residing at Waxahachie, in the county of Ellis and State 5 of Texas, have invented certain new and useful Improvements in Moldboards for Plows, of which the following is a specification.

The present invention relates to an improvement in mold-boards in which the 10 shedding surface is made from porous material, such as plaster of Paris or the like, which material experience has shown to be satisfactory for use in certain classes of sticky soil.

15 The invention has reference more particularly to the provision of a mold-board having a removable element of plaster of Paris, by which term I shall hereafter, in both the specification and claims, include materials of 20 similar compositions, suitably reinforced or strengthened and made separable from the metal backing or casing to which it is attached, so that it can be made separate at a factory, shipped to the farmer, and by him 25 attached to or removed from the backing or casing at will.

Experience has shown that certain soils, such as the gumbo or black waxy soil of 30 Texas, will stick or adhere to a steel or other hard smooth surface to such an extent that a moldboard plow having such a surface will very quickly become clogged and caked with dirt, and so that it will soon cease to cut a furrow or stay in the ground until cleaned, 35 which necessitates frequent stoppages for such purpose. On the other hand, experience has shown that when the discharging surface of the mold-board is made of plaster of Paris, such soils will not stick to but will 40 be freely shed from it. The moisture of the soil will enter the pores of the material composing the mold-board and lubricate the surface of the same, so that a mold-board having such a surface will not clog or cake even 45 in such soils as the waxy gumbo soil of Texas. It has been found, however, that such porous material wears rapidly when subjected to continuous use. Therefore, the 50 useful life of a porous surface element is very short, and the life of the entire mold-board is limited to that of the porous mate-

rial when such material constitutes an integral portion of the mold-board. Such life being comparatively short, renewal of the entire structure must be made at frequent 55 intervals, with resulting inconvenience to the farmer and greatly increased expense.

The main object of my present invention is to meet the aforementioned objections to mold-board plows having porous shedding 60 surfaces. I do this by providing a construction in which the porous surface element is separate from the backing or casing which supports it, and which surface element is so made and reinforced as to have sufficient 65 mechanical strength to withstand the rough treatment which it will receive in storage, shipment to the farmer, and attachment to the metal backing or casing on the plow.

In other words, the main object of my 70 present invention is to provide a reinforced surface element, of plaster of Paris, so made and strengthened or reinforced that it can be manufactured at a suitable plant, safely shipped to the farmer, and by him adjusted 75 or attached to the metal backing or casing of his plow. Thus, to provide a mold-board plow having all of the desirable characteristics of one which has a porous shedding surface and is consequently adapted for use in 80 sticky soils, without the attendant disadvantages, excessive cost, etc., which have heretofore accompanied such a device.

Other objects and uses will appear from a detailed description of the invention, 85 which consists in the features of construction and combination of parts hereinafter described and claimed.

In the drawings, Figure 1 shows a face view of a mold-board provided with the removable surface element to which this invention relates; Fig. 2 shows a section taken partly at the surface of reinforcement; and Fig. 3 shows a cross section taken on line 3-3 of Fig. 2, looking in the direction of 90 the arrows.

In the drawing, the metal backing or casing which is adapted to receive the porous surface element is designated by the numeral 4. It is in the form of a pan, preferably of metal and warped or curved to the proper mold-board contour and having its 100

rims 5 upturned around its periphery. The removable porous element 6 is adapted to seat within such pan and conforms to the contour thereof, having its discharging or 5 shedding surface 7 substantially flush with the outer edges of the upturned flange 5. In other words, the mold-board, when completed, comprises two distinct elements, namely, the metal pan or backing, and the 10 removable porous element which is adapted to lie uniformly in said pan and conform to its contour. As a general proposition, the porous element, as already said, is made from plaster of Paris or other like material. 15 Therefore, it is comparatively brittle and will not withstand rough handling or treatment without fracturing or breaking. Consequently, an element formed of such material without reinforcing could not safely be 20 subjected to the rough usage and handling which it would ordinarily receive in manufacture and shipment from a factory to the farmer or local dealer. To meet this difficulty, I provide a reinforcement which is 25 embedded in the material of the porous element itself and really becomes a portion of such element. In the particular construction illustrated, this takes the form of a wire screen 8 or the like, the meshes of 30 which are filled with, and the wires of which are surrounded and covered by, the porous material itself. The gage of the wire of such reinforcement, and the size of the openings therein, will be adjusted to the particular requirements of the element which is 35 being molded, such as its size, thickness, etc. It is simply desired to reinforce the porous element to that extent necessary to give it the requisite strength, exemption from 40 breakage, and make its shipment and handling safe until it is connected to the metallic pan or backing. Thus the farmer can buy the porous elements, have them shipped to the point of delivery, and then 45 set them in or attach them to the backing or casing of his plows as needed.

As a general proposition, the surface pressure of the earth will hold the porous element back in the casing when once seated, 50 so as to keep it properly seated in the same. However, in order to prevent the porous element from falling out of the pan when the mold-board is not being used in plowing, and the surface pressure thus removed, I 55 have provided means for attaching the porous element to the pan. In the particular construction illustrated, such means comprise a threaded socket 9 or the like, which is cast into the porous element and really 60 comprises a portion of the same. A tap nut 10 may then be passed through the pan from the back thereof and screwed into such socket to secure the necessary connection between the parts.

65 The hardness of the material used in mold-

ing the porous elements may be determined by the characters of the soils in which they are to be used. I have found by experience that a composition composed of a mixture of plaster of Paris and cement is in general 70 best adapted for this service, and that by varying the percentages of these materials the hardness of the resulting porous element can be adjusted to that extent necessary to adapt the mold-board for use in different 75 classes of soil. As a general proposition, the variation of this percentage will be between the limits of five per cent. (5%) cement and ninety-five per cent. (95%) plaster of Paris, and twenty-five per cent. (25%) cement and seventy-five per cent. (75%) plaster of Paris. However, I do not limit myself to any particular composition of material, except as may be hereafter called for in the claims, but I include within the scope 85 of my invention any composition, or any material of a porous nature, reinforced in a suitable manner, so that it may constitute a separate and separable element from the backing into which it is to be inserted, and 90 which may be safely shipped and handled prior to insertion into and connection with said backing, and which may be applied to and removed from its metal backing or seat without the necessity of skilled assistance. 95

I claim:

1. In a two-part mold board, the combination with a back section in the form of a pan of desired contour and configuration according to the desired shape of the mold 100 board, said pan being provided with a peripheral flange having its inner face beveled outwardly, of a removable section seated into said pan and of the same contour and configuration as the pan and having its periphery beveled to seat against the flange of the pan, said removable section being formed of moisture absorbing and soil shedding material, and being of a thickness substantially equal to the height of the peripheral flange on the pan, a reinforcing netting 105 completely embedded in the material of the removable section, and means for temporarily securing the removable section in place within the pan, whereby the removable 110 section may be directly seated into the pan, by moving the same directly toward the pan.

2. In a two-part mold board, the combination with a back section in the form of a 120 pan of desired contour and configuration according to the desired shape of the mold board, said pan being provided in its periphery with forwardly projecting supporting means having their inner surfaces beveled 125 outwardly, of a removable section seated into said pan and of the same contour and configuration as the pan and having its periphery beveled to seat against the flange of the supporting means, said removable section be- 130

ing formed of moisture absorbing and soil shedding material, and being of a thickness substantially equal to the height of the supporting means, a reinforcing netting completely embedded in the material of the removable section, and means for temporarily securing the removable section in place with-

in the pan, whereby the removable section may be directly seated into the pan, by moving the same directly toward the pan.

CHARLES K. MILLER.
